SLEEPING BAG

Harry E. Hunt, Boulder, Colo., assignor to Alpine
Designs, Inc., Boulder, Colo.

Filed Aug. 21, 1972, Ser. No. 282,347

Term of patent 14 years

Int. Cl. D6—13

U.S. Cl. D6—201

FIG. 1

FIG. 2

FIG. 3

FIG. 4

FIG. 5

FIG. 6

FIG. 7

FIG. 1 is a perspective view of a sleeping bag showing my design;

FIG. 2 is a top plan view thereof;

FIG. 3 is a front elevational view;

FIG. 4 is a bottom plan view thereof;

FIG. 5 is a rear elevational view;

FIG. 6 is an enlarged scale left side elevational view; and

FIG. 7 is an enlarged scale right side elevational view.

The characteristic feature of the design resides in the particular configuration and arrangement of the head and neck portion in combination with the shoulder portion.

I claim:

The ornamental design for a sleeping bag, as shown and described.
